UNITED STATES PATENT OFFICE.

PHILIP G. DARLING, OF BRIDGEPORT, CONNECTICUT, ASSIGNOR TO MANNING, MAXWELL & MOORE, INC., OF NEW YORK, N. Y., A CORPORATION OF NEW JERSEY.

SAFETY VALVE.

Application filed July 2, 1921. Serial No. 482,047.

To all whom it may concern:

Be it known that I, PHILIP G. DARLING, a citizen of the United States of America, and resident of Bridgeport, in the county of 5 Fairfield and State of Connecticut, have invented new and useful Improvements in Safety Valves, of which the following is a specification.

This invention concerns steam safety 10 valves and relates more particularly to that type of valve device wherein the operation of the main valve is controlled by a pilot valve of relatively small dimensions.

The tendency of modern steam engineering practice is toward the production of 15 larger and larger boiler units having high evaporative efficiencies with extremely rapid steam production, while the working pressures employed have correspondingly increased. Under these circumstances, the 20 provision of safety valve devices having discharge capacities commensurate with the rate of steam production has become increasingly difficult. In many instances recourse has 25 been had to the multiplication of valves in order to provide the desired discharge capacity, this however, being contrary to good boiler practice which demands that the number of openings in the boiler shall be kept 30 as low as possible.

If vertical lift valves are employed on 35 marine boilers, it is often necessary to remove the entire valve from the boiler when it is desired to regrind the valve seat on account of the limited head room above the 40 boilers which makes it impossible to do such work while the valve is in position, thus greatly increasing the time necessary to perform this operation.

When it is attempted to load a valve of 45 large capacity, such for example as is employed in locomotive or naval practice, by means of a spring, this spring must necessarily be extremely heavy. Such a spring, however, does not respond quickly to small 50 variations in pressure and it is difficult under such circumstances to keep the blow down of the valve within the desired limits, which in certain cases are precisely described by law,— or to adjust such limits when circumstances 55 so demand. This difficulty, however, is much less apparent when the total load upon the valve is small and when a relatively light spring may be employed. Certain attempts,

therefore, have been made to provide large 55 capacity safety valves having a small or pilot valve for determining their operation, but in most instances such pilot valves have been arranged to constitute integral parts of the main valve structure, thus materially 60 adding to the size, complexity, and expense of manufacture of the latter, and being in many cases of such a character as would make it difficult to keep them in working order. In some cases the pilot valve is employed 65 as a fluid motor for actuating a relief valve which serves as the immediate means for controlling the main valve. In the design of such an arrangement, however, great care must be exercised in order that any 70 failure or breakage of the parts of such pilot or relief valve or of the conduits connecting them with the main valve, shall not result in failure of the latter to function. Moreover, if the pilot valve be directly connected 75 to the relief valve, or other part to be operated, it is clear that the load imposed by the latter is added to that of the pilot valve spring in opposing the lift of the pilot valve, thus in some instances at least, rendering the action of the latter uncertain, where- 80 as substantial accuracy of operation is a prime requisite in a safety valve device.

The principal object of the present invention is to so design a safety valve device as 85 to furnish the desired capacity to enable it properly to meet the demands of a boiler of any size, while at the same time restricting the external dimensions of the valve casting and particularly the vertical height 90 of the same whereby to permit of its use where the head room above the boiler is very limited. A further object is to so design such a valve device as to permit of the regrinding of the valve seat without removing 95 the valve from position, even though the head room above the boiler be very small. A further object is to provide for controlling the main valve by the use of a pilot valve comprising a small capacity safety valve of 100 ordinary commercial form having a relatively light, adjustable spring, and the usual adjustable blow down ring, thus permitting the blow down of the main valve to be kept within precisely defined limits, while at the 105 same time allowing of adjustment of the blow down even when the main valve is under full pressure.

It is also an object of the invention to make such pilot valve as an independent unit detachably connected to the main valve casing and to utilize such pilot valve as a fluid motor whereby to actuate an adjustably loaded relief valve serving as the immediate means for controlling the main valve, the parts being so arranged as to permit the pilot valve to lift from its seat to a predetermined extent before it encounters any opposition from the relief valve spring. Subsidiary to this latter object is the design of the relief valve in such manner as to make unnecessary the employment of a heavy spring for retaining it against its seat, and the provision of means whereby said pilot and safety valves may be secured against surreptitious adjustment by unauthorized persons.

A further object of the invention is to so design the main and controlling devices that upon breakage of the latter, or of the connecting conduits employed, the main valve will blow automatically, thus giving notice of such breakage, while at the same time avoiding any possibility that the main valve may fail to function at the proper time.

While the above objects may undoubtedly be attained in various ways, the arrangement disclosed in the accompanying drawings is illustrated as exemplifying means well adapted for carrying the present invention into effect. In such drawings,—

Fig. 1 is an elevation of the complete valve device looking into the discharge end of the main valve casing;

Fig. 2 is a plan view of the device shown in Fig. 1;

Fig. 3 is a vertical cross section through the main valve casing and on the axis of the main valve;

Fig. 4 is a vertical cross section to enlarged scale through the pilot valve and the associated parts, the section being taken on a plane parallel to the axis of the main valve;

Fig. 5 is a view similar to Fig. 4 but illustrating a modified form of relief valve, certain of the parts being broken away; and

Fig. 6 is a fragmentary detail in section illustrating a modified form of the main valve and its seat.

Referring particularly to Figs. 1 and 2, the main valve casing is indicated at 1, such casing being of substantially T-shape in vertical section as indicated in Fig. 3. This casing comprises the vertical leg 2 and the horizontally extending member 3. The member 2 may be provided at its lower end with a radial flange 4 if desired. The member 2 is provided with a vertical passage 5, the lower end of this passage being internally screw threaded for engagement with the upper end of a nipple or pipe 6 leading from the boiler. The horizontal portion 3 of the casing provides a substantially horizon-

tal bore 3^a which adjacent to its end 7 is internally screw threaded for the reception of the threaded extremity 8 of a discharge pipe connection 9 leading to any suitable point of discharge. The opposite end of the member 3 is provided with an external flange 10 with which engages a cover plate 11 for closing the horizontal bore at that end. This cover member is removable but is normally secured in position by means of a plurality of bolts such as indicated at 12. Concentric with the bore 3^a there is provided a flange 13 extending from the inner wall of the casing, such flange being provided with internal screw threads which engage an externally threaded annular ring 14. This ring 14 constitutes the main valve seat, and by arranging it as an independent element it may readily be formed of a non-corrosive material different from that of the casing, and when worn may easily be replaced. The ring 14 provides an opening 15 through which steam from the passage 5 may be discharged into the portion 7 of the bore 3^a. In the closed end of the bore 3^a, there is arranged a sleeve 16 of any suitable non-corrosive material, such for example as bronze, forming a cylinder within which slides a piston member 17. This piston member has a portion 18 of reduced diameter, thus providing a shoulder 19 between the main portion of the piston and such reduced portion. The reduced portion 18 terminates in an element 20 engageable with the seat 14, the member 18 thus constituting the main valve for controlling the opening 15. In accordance with the preferred arrangement, the element 20 of the valve member 18 is bevelled inwardly to cooperate with a similarly bevelled surface of the ring 14.

Projecting centrally from the member 18 is a guide stem 21 which slidably engages within a sleeve 22 supported in a spider 23, such spider comprising the legs 24 extending integrally from the inner wall of the casing member 3. The space between the inner surface of the cover plate 11 and the piston 17 forms a chamber 25 into which steam may leak from the passage 5, the piston for this purpose being slightly loose in the cylinder 16. With this arrangement, the normal pressure within the chamber 25 is substantially that of the passage 5. An opening 26 leads outwardly from the chamber 25 through the flange 10, the outer portion of such opening being screw threaded for engagement with a pipe connection 27. Secured in this pipe connection is one extremity of a pipe 28, the purpose of which will be described at length hereinafter.

Referring to Fig. 1, there is indicated a bracket 29 preferably formed integrally with the casing member 2 and extending laterally therefrom. This bracket is provided with a

substantially horizontal upper surface 30 and is continued within the casing member 2 in the form of a projecting lug 31. Extending upwardly from the lower end of 5 this lug and through the bracket 29 is an open ended passage 31^a. A flanged collar 32 is secured upon the surface 30 of the bracket 29 by means of bolts 33, such collar being provided with an internally screw 10 threaded opening with which engages the threaded lower end 36 of a pilot valve casing 37. This casing comprises an inlet chamber 38 which communicates with the chamber 5 by means of the passage 31^a through the 15 bracket 29.

The pilot valve casing is also provided with a discharge chamber 39 from which extends the internally screw threaded nipple 40. Connected with the nipple 40 is a pipe 20 41 which extends through an opening in the side wall of the discharge end 7 of the bore 3^a terminating within the latter as indicated at 42 (Fig. 3). The opening in the wall of the casing 3 for the reception of the pipe 41 25 may be provided with suitable packing as indicated at 43. Between the chambers 38 and 39 of the pilot valve casing is an annular valve-seat 44 with which cooperates a valve 45, this valve being of the poppet type and 30 having guide fins 46^a extending down into the chamber 38. The valve 45 is also provided with a radial flange 46 which cooperates with an adjustable blow down ring 47, such ring having screw threaded engagement 35 with an annular flange 47^a surrounding the valve seat. This ring may, if desired, be provided with a series of spaced notches as 48 with which may engage a locking pin or screw 48^a for retaining the blow 40 down ring in properly adjusted position.

Extending upwardly from the valve 45 is a valve stem 49 connected to the valve in any desired and known manner. This stem passes up through the upper end of the 45 casing 37 and through an externally screw threaded sleeve 50 whereby the upper end of said stem is guided. The sleeve 50 has a head 51 of square or hexagonal shape with which a wrench or other suitable operating 50 tool may be engaged and is provided with a lock nut 52 for retaining such sleeve in adjusted position. Secured to the stem 49 at a point immediately above the valve 45 is a collar member 53, such collar member having an upstanding boss preferably provided with a spherical outer surface with which engages a spherical socket formed in the lower side of a plate 54. Resting upon the plate 54 is a coiled spring 55 which surrounds the stem 49, the upper end of such spring bearing against a second plate 56 which engages the lower end of the adjusting sleeve 50. By turning the sleeve 50, the tension of the spring 55 may be adjusted. 60 If desired, a lever 57 may be provided for

manually lifting the valve 45 from its seat, such lever being of usual and well known construction.

Extending upwardly from the upper end of the casing 37 is a secondary casing 58. 70 This casing may, if desired, be integral with the casing 37, but as herein illustrated, comprises an independent member having screw threaded engagement with the casing 37 as at 58^a and locked thereto by means of bolts 59 or in other desired manner. The casing 58 is of generally cylindrical form and one side of said casing is provided with an opening of substantial size normally closed by a door 60 hinged at 61 to the main portion of 75 the casing. This door is provided with an apertured lug 60^a adjacent its free edge, such lug cooperating with a similar lug 60^b projecting from the outer surface of the casing 58. The shackle of a pad-lock 110 may be passed through the apertures in the respective lugs thus serving to lock the door against opening by unauthorized persons. Rotation of the casing 58 relatively to the 80 casing 37 by reason of the threaded connection between the two would alter the operation of the valve device as will hereinafter be described and to prevent surreptitious turning of the casing 58, the heads of the bolts 59 may be provided with transverse 85 openings through which may be passed a wire or cord 64, the ends of which may be secured together by a seal 65.

Casing 58 is provided with one or more openings such as 66 for the escape of steam from the interior thereof. At its upper end, the casing 58 is provided with a valve chamber 67, having annular valve seats 68, 69 at its upper and lower end, respectively. Cooperating with the valve seats 68, 69 are the heads 70, 71, respectively, of a vertically movable valve 72, such valve being provided with guide fins or other suitable means for properly guiding it in its movement. Projecting downwardly from the lower head 71 and through the valve seat 69 is a valve stem 73, such valve stem being provided with a diametral open ended slot within which is received the looped upper end 74 of a rod 75 constituting an extension of the stem 73. Through the looped end of the rod 75 extends a rivet or pin 76, whereby such rod is pivotally connected to the stem 73. The rod 75 is axially aligned with the stem 49 of the pilot valve, the adjacent ends of such rod and stem normally being spaced apart as indicated at 78^a. By rotating the casing 58 relatively to the casing 37 this space may be varied, thus altering the amount of movement of stem 49 necessary to bring it into contact with the lower end of stem 75. An annular rib 77 extends downwardly into the casing 58 concentric with the stem 73, such rib serving to position 100 the upper end of a coil spring 78 which is 95 105 110 115 120 125 130

arranged within the casing 58 and which surrounds the rod 75. The lower end of the spring 78 rests against a plate 79 provided in its lower surface with a spherical cavity 5 engaging a spherical surface provided upon a nut 81 which engages screw threads upon the lower end of the rod 75. For retaining the nut 81 in adjusted position, a lock nut 82 may be provided. By adjusting the 10 nut 81, the tension of the spring 78 may be varied and thus the resistance of the valve, comprising the heads 70, 71 to opening under pressure, may be varied. The head 70 of the valve 72 is of somewhat greater 15 area than the head 71 and thus when subject to pressure, the valve tends to open, this tendency, however, being normally counteracted by the spring 78. As the valve head 70 is but slightly larger than the head 20 71, the valve may be considered, however, as substantially balanced, and thus the spring 78 may be relatively light so that little force is required to open the valve. Leading from the chamber 67 is a passage 25 formed in an outstanding and externally screw threaded nipple 85. The pipe 28 previously referred to, is secured to the nipple 85 by means of the coupling 86 or in other desired manner, permitting the disconnection of the parts.

In the arrangement illustrated in Fig. 5, the pilot valve casing is indicated at 37^a and its spring at 55^a. The stem of the pilot valve, indicated at 49^a, extends upwardly 35 and into the casing 58^a of the relief valve. The latter casing is supported upon bracket arms 100, extending upwardly from a ring 101 suitably mounted upon the top of the casing 37^a. The relief valve casing 58^a has a 40 valve chamber 67^a provided at its upper and lower portions with annular valve seats 68^a, 69^a, respectively. With such seats cooperate the valve heads 70^a, 71^a, respectively, of a valve member 72^a which is vertically slideable 45 within the casing 58^a. From the lateral wall of the casing 58^a extends a threaded nipple 87^a to which the end of the pipe 28 is connected by means of a coupling 86^a. The valve stem 49^a passes freely up through 50 a central opening in the valve 72^a and is screw threaded at its upper extremity as indicated at 102. Engaging such screw threaded extremity is a nut 103 which bears upon the upper surface of a plate 104. A 55 coil spring 105 surrounds the upper portion of the stem 49^a and bears against the plate 104, the lower end of such spring resting upon a plate 106. The latter plate is supported upon a boss 107 projecting up from 60 the valve 72^a above the valve head 70^a. At a point below the lower surface of the casing 58^a a collar 108 is secured to the valve stem 49^a, such collar being adjustable thereon if desired. The valve 72^a is provided with an 65 annular extension or stem 109 extending

downwardly below the valve head 71^a and in a position to be engaged by the collar 108 as the stem 49^a of the pilot valve rises. If the collar 108 be adjustably secured to the stem, it is evident that the amount of lift 70 of the pilot valve stem 49^a before such collar 108 strikes the member 109 may be varied at will.

In the arrangement shown in Fig. 6, the main valve member 18^x, cooperates with a valve ring 14^x having screw threaded engagement with the flange 13^x. The valve is provided with a guiding stem 21^x cooperating with a sleeve 22^x as in the arrangement previously described. In the arrangement shown in this figure, however, the end surface of the valve member 18^x is substantially flat and cooperates with the radial surface 20^x of the valve seat ring. While it is preferred to employ beveled coacting surfaces, the arrangement illustrated in this figure may be found desirable under certain conditions of use.

In the operation of the mechanism illustrated in Figs. 1 to 4, it being assumed that the pipe or nipple 6 is connected to a boiler, steam at full boiler pressure will be admitted to the chamber 5. Steam will also be admitted to the chamber 38 of the pilot valve, passing thereto through the channel 31^a. Steam also leaks by the piston 18 and into the chamber 25 and by reason of the fact that the area of the piston 17 is greater than the area of the valve 18, the pressure in the chamber 25 serves to retain the valve 18 against its seat 14, thus preventing the escape of steam from the chamber 5 into the discharge end 7 of the bore 3^a. Steam passing into the chamber 25 also passes through the conduit 28 and builds up pressure in the chamber 67 of the relief valve 72. If the boiler pressure rises to a point sufficient to overcome the tension of spring 55, the valve 45 will be raised from its seat, the steam which blows out between this valve and its seat passing into the discharge chamber 39 and through the pipe 41 into the discharge end of the main valve casing and thence out through the discharge pipe 9. Such steam is thus prevented from escaping into the room or space in which the safety valve mechanism is located. As the steam passes out below the flange 46 of the valve 45, the energy of the steam tends to lift such valve to its full open position and the effect of such escaping steam may be varied in well known manner by means of the adjustable blow down ring 47.

As the valve stem 49 rises with the valve 45, its upper end comes into contact with the lower end of the stem 75 and upon further lifting of the valve 45, the valve 72 is unseated. Immediately upon unseating of the valve 72, the steam contained in chamber 25 is permitted to flow out through the 125 130

conduit 28 and to escape through the upper and lower valve seats of the valve 72. Such steam being in relatively small quantity may be permitted to pass out through the openings 66 and 84 into the surrounding atmosphere without causing any substantial annoyance to persons located nearby. As soon as the pressure in chamber 25 is relieved, the boiler pressure, acting upon the valve 18 and upon the shoulder 19 serves to slide the piston 17 to the left as viewed in Fig. 3, thus opening the main valve to full extent and permitting steam to blow freely out through the valve seat 14 and through the discharge pipe 9. As the opening through the valve seat 14 is substantially unobstructed, steam may be discharged therethrough in very substantial amount, it being found experimentally that with a valve of this character, having a seat opening of approximately three inches in diameter, as great a quantity of steam can be discharged as through four $4\frac{1}{2}$ " valves of ordinary construction. As soon as the boiler pressure decreases to the desired amount, the spring 55 returns the valve 45 to its seat, such action being controlled as above pointed out by the adjustment of the blow down ring 47. Immediately upon closing of the valve 45, the spring 78 returns valve 72 to closed position and pressure builds up in the chamber 25 of the main valve casing, whereupon the piston 17 moves to the right and closes the main valve. It is thus evident that by reason of the arrangement of parts above described, the blow down of the main valve depends entirely upon that of the pilot valve 45, and as the latter valve may be of relatively small diameter, the spring 55 may be made very sensitive to variations in pressure and thus the blow down of the valve 45 may be adjusted with great nicety. By reason furthermore of the fact that the valve stem 49 is normally spaced a short distance 78^a from the lower end of the stem 75, the valve 45 is permitted to rise to a slight extent from its seat before encountering any opposition from the spring 78 and associated parts. This permits of the regulation of the valve 45 solely by means of the spring 55, the additional force necessary to lift the valve 72 being provided by the kinetic energy of the steam escaping over the valve seat 44. By arranging the adjusting means for the springs 55 and 78 within the casing 58, it is possible to adjust them with the least possible trouble while at the same time the casing provides means for enclosing such adjusting devices whereby tampering with the same by unauthorized persons may be prevented. This is especially desirable in those cases where it is required that the valve springs be set or inspected by authorized officials who may, with the present arrangement, seal the casing, after ad-

justing the valves, by means of the wire and seal above described.

By arranging the main valve casing to discharge in a horizontal direction and by providing the horizontally moving valve, it is possible to reduce the vertical height of the casing to a minimum, thus permitting the placing of the valve in locations where the head room above the boiler is very small. It is also evident that by removing the cover plate 11, the main valve, including the piston 17, may readily be removed from the casing, and as the valve seat is then exposed it may be reground or replaced without necessitating the removal of the valve casing from the boiler, even though the head room above the boiler be restricted. The pilot valve device as hereinbefore described is substantially like safety valves of ordinary commercial type and such a valve may be utilized for this purpose, it being merely necessary to provide suitable means for mounting the casing thereon. It is also evident that by mounting the pilot valve and the relief valve in separate casings and connecting them to the main casing by means of pipes, they may readily be removed from the main valve casing for repairs or replacement, thus avoiding the necessity of replacing the entire valve structure when one of its component parts is broken or injured. By forming the valve 72 in the manner above described, that is to say, with its upper head slightly larger than its lower head, it is clear that if its spring should be broken, the valve would lift automatically, thus blowing the main valve and giving notice of such injury while at the same time insuring the apparatus against failure to operate by reason of such breakage. Breakage of the pilot valve spring 55 would also result in the same way, while any breakage of the pipe connection 28 would immediately serve to relieve the pressure in the chamber 25, thus again causing the main valve to blow. Except when blowing the main valve 18 is held against its seat 14 by full boiler pressure acting upon the end of piston 17; thus the valve is held much tighter and more firmly against its seat than is a valve of ordinary design wherein the force of the closing spring is nearly balanced by the steam at working pressure acting against the under side of the valve.

The arrangement shown in Fig. 5 operates in substantially the same manner as that above described but fails to provide means for enclosing the spring 105 or for preventing surreptitious adjustment of the springs 105 and 55^a by unauthorized persons. While this device may be desirable under certain circumstances, that illustrated in detail in Fig. 4 is preferred.

Having thus described the invention in

- a preferred embodiment of the same together with the mode of operation thereof, what I claim and desire to secure by Letters Patent of the United States is:
5. 1. A safety valve device comprising a casing, a valve seat therein, a main valve co-operable with said seat and normally held to the seat by fluid pressure, a fluid motor independent of said casing, and means 10 actuated by the fluid motor after a predetermined interval of operation thereof for relieving the seating pressure on the main valve. 70
  15. 2. A safety valve device comprising a casing, a valve seat therein, a movable main valve co-operable with said seat and normally held to its seat by fluid pressure, a spring loaded pilot valve independent of said casing, and means actuated by the pilot 20 valve after a predetermined movement of the latter for relieving the seating pressure on the main valve. 80
  25. 3. A safety valve device comprising a casing having a vertical inlet passage and a horizontal discharge passage communicating therewith, a horizontally movable main valve, a seat therefor, a pressure actuated piston normally holding the main valve against its seat, a fluid motor independent 30 of said casing comprising a movable element whose movement is initiated at a predetermined pressure, and means actuated by said element after a predetermined interval of its movement for relieving the pressure 35 upon the piston of the main valve to allow the latter to open. 85
  40. 4. A safety valve device comprising a casing having a substantially vertical inlet passage, a substantially horizontal discharge passage, a horizontally movable main valve normally closing said discharge passage, a pressure actuated piston for moving said valve, a relief valve for relieving the pressure at one side of the piston, a pressure operated pilot valve having a loaded valve member, and means actuable by said loaded member after a predetermined movement of the same under pressure to open the relief valve. 105
  45. 5. A safety valve device comprising a main valve casing, a second casing containing a relief valve, and a casing containing a pilot poppet valve, said relief and pilot valve casings being removable as a unit from the main valve casing. 110
  50. 6. A safety valve device comprising a main valve casing having a valve movably mounted therein, a relief valve casing having therein a valve for determining the actuation of the main valve, and a pilot valve casing having a poppet valve therein for actuating the relief valve. 115
  55. 7. A safety valve device comprising a main valve casing having inlet and discharge passages, a relief valve casing independent of 60 the main valve casing, a conduit connecting said casings, a pilot valve casing having a poppet valve therein, and conduits connecting the latter casing with the inlet and discharge passages of the main valve casing respectively. 120
  65. 8. A safety valve device comprising a main valve casing having inlet and discharge passages, a main valve within said casing, an independent casing having a poppet valve therein, connecting passages between said poppet valve casing and the inlet and discharge passage respectively of the main valve casing, and means actuatable by the poppet valve for controlling the movements of 80 the main valve. 125
  70. 9. In combination with a pressure operated main valve, a fluid motor device for determining the actuation thereof, said motor device comprising a relief valve and a spring pressed poppet valve, the latter being subjected to substantially the same pressure as that upon the main valve, and means for adjusting the blow down of said poppet valve. 130
  75. 10. A safety valve device comprising a pressure actuated main valve, a relief valve for determining the actuation of said main valve, a pilot poppet valve for controlling the relief valve, and means for determining the blow down of said pilot valve while the main valve is under pressure. 90
  80. 11. A safety valve device comprising a pressure controlled main valve, a relief valve for determining actuation of the main valve, a pilot valve of the poppet type controlling the relief valve, said pilot valve having spring means normally operative to close the same, means admitting pressure to said poppet valve, and means for adjusting the blow down of said latter valve while both valves are subjected to full pressure. 100
  85. 12. A safety valve device comprising a pressure actuated main valve, a relief valve for controlling the opening and closing of said main valve, a pilot valve determining actuation of the relief valve, said pilot valve being of the poppet type, a spring normally operative to close said pilot valve, and an adjustable blow down ring associated with said pilot valve for determining the blow down of said valve and thereby that of the main valve. 110
  90. 13. The combination with a pressure actuated main valve, of a device for controlling such a valve, said device comprising a casing having a spring pressed relief valve therein, a spring pressed poppet valve for controlling said relief valve, and means for adjusting the tension of the springs of each of said valves. 120
  95. 14. A valve device comprising an elongated casing having a valve seat adjacent one extremity, a valve engageable therewith, a spring within the casing for controlling said valve, means within the casing for ad- 130

justing the tension of said spring, a pilot valve for raising said first named valve from its seat, a spring for controlling said pilot valve, adjusting means for said spring within said casing, and an operable closure for said casing giving access to both of said adjusting means.

15. In combination with a main valve, a relief valve for determining actuation of the main valve, a pilot valve for actuating the relief valve, springs for urging each of said valves toward its seat, means for adjustably tensioning each of said springs, and a common casing enclosing said tension adjusting means.

16. A valve device comprising a substantially cylindrical casing, a valve seat adjacent one end thereof, a valve member, a spring normally operative to hold said valve member against its seat, means within said casing for adjusting the tension of said spring, and a hinged door forming a portion of the cylindrical wall of the casing and serving to give access to said adjusting means.

17. A safety valve device having a pressure operated main valve and means for controlling the operation thereof, said means comprising a casing having a pressure operated poppet valve therein, and a secondary casing removably secured to said poppet valve casing and having therein a relief valve operable by movement of the poppet valve.

35. 18. A valve controlling device comprising a relief valve, a pressure actuated valve for operating the same, springs for urging said valves toward their respective seats, means for adjusting the tension of said springs, a casing for enclosing said adjusting means, said casing having an openable closure, and means whereby said closure may be secured against surreptitious opening.

45. 19. A valve device comprising a casing having a valve seat, a valve movable toward and from the same, a second valve casing having a poppet valve housed therein and a freely open outlet port for discharge of fluid passing the poppet valve, and mechanical means for transmitting movement of the poppet valve to said first valve, the parts being so constructed and arranged as to permit sub-

stantial movement of said poppet valve prior to movement of said first named valve.

20. A valve device comprising a casing having a valve seat, a valve movable toward and from the same, means normally holding said valve against its seat, a second valve casing having a poppet valve therein, said casing having a freely open outlet port for delivery of fluid passing the poppet valve and mechanical means for transmitting movement of the poppet valve to said first named valve to lift the latter from its seat, said mechanical means providing for lost motion between said valves.

21. A valve device comprising a valve seat and a valve normally engaging the same, said valve having a projecting stem, a valve casing housing a poppet valve, said casing having an open outlet port for the delivery of fluid passing the poppet valve, and a stem carried by the poppet valve, the respective stems providing normally spaced elements, constructed and arranged for operative contact upon a predetermined lift of said poppet valve.

22. A spring pressed valve member having a stem projecting therefrom, a valve casing housing a poppet valve, said casing having a freely open discharge port, the poppet valve having a stem aligned with said first stem, the adjacent ends of said stems normally being spaced apart whereby said poppet valve is permitted to lift a substantial amount under excess pressure before being subjected to the load of said spring pressed valve.

23. A safety valve device comprising a main valve casing, a main valve therein, and a relief valve device for determining the actuation of the main valve, said relief valve device comprising a casing having a pair of spaced, co-axial valve seats, a valve member having elements simultaneously engageable with said seats, a conduit leading from the space between said valve seats to the main valve casing, and a poppet valve having an adjustable blow down for moving said valve member whereby to disengage it from its seats.

Signed by me at Bridgeport, Conn., this 21st, day of June, 1921.

PHILIP G. DARLING.
